UNITED STATES PATENT OFFICE.

CLARENCE E. CLOSSON, OF POTLATCH, IDAHO.

ADVERTISING-CABINET.

1,393,665.

Specification of Letters Patent. Patented Oct. 11, 1921.

Application filed February 3, 1920. Serial No. 355,900.

To all whom it may concern:

Be it known that I, CLARENCE E. CLOSSON, a citizen of the United States, residing at Potlatch, in the county of Latah and State 5 of Idaho, have invented certain new and useful Improvements in Advertising-Cabinets, of which the following is a specification.

This invention relates to an improved advertising cabinet and has as one of its principal objects to provide a device of this character which may be employed as an automobile or other vehicle body whereby the vehicle may be driven about for exhibiting 15 a sign displayed by the cabinet.

The invention has as a further object to provide a cabinet having apertured side walls and employing means in connection with said apertures whereby any desired 20 apertures may be uncovered for forming sign letters.

A further object of the invention is to provide a cabinet which may, at night, be illuminated so that the light will shine 25 through the uncovered apertures forming the sign letters and also wherein colored shutters will be provided for covering the apertures so that, in the day time, the apertures forming the letters will be distinguished 30 by the color of the shutters.

A still further object of the invention is to provide a cabinet wherein the side walls thereof will be removable so that while one pair of side walls is in use, another pair 35 may be made ready for use.

And the invention has as a still further object to provide in connection with the cabinet, side walls of slightly different construction whereby letter stencils may be employed upon the side walls.

Other and incidental objects will appear hereinafter.

In the drawings:

Figure 1 is a perspective view showing my 45 improved advertising cabinet employed as the body of a motor truck of conventional type,

Fig. 2 is a fragmentary perspective view looking at the inner side of one of the side 50 walls of the cabinet and illustrating the mounting of the shutters thereon,

Fig. 3 is a perspective view showing one of the shutters and its socket in detail,

Fig. 4 is a fragmentary perspective view 55 showing one of the doors at the rear of the cabinet swung open,

Fig. 5 is a transverse sectional view taken through the cabinet.

In carrying the invention into effect, I employ a cabinet body 10. This cabinet 60 body is preferably formed of sheet metal and may be of any preferred shape. However, in the drawings, I have shown the cabinet body constructed to form the body of a conventional type of motor truck, so that the 65 truck may be driven about for exhibiting a sign or signs displayed by the cabinet. Nevertheless, the device may, as will be appreciated, be employed as a stationary cabinet. The side walls of the cabinet are, for convenience, indicated at 11, these side walls being detachably secured in position, as particularly illustrated in Fig. 5, by screws or other suitable fastening devices. Arranged within the cabinet are parallel longitudinal 70 partitions 12 defining light chambers 13 at opposite sides of the cabinet and an intervening battery chamber 14. Normally closing these chambers at the rear end of the cabinet are doors 16. Thus, when desired, 75 access may be readily had to said chambers. As brought out in Fig. 1, each of the side walls 11 of the cabinet is formed with an apertured area or field about which is an imperforate border. The apertures are indicated at 17. Mounted within each of the 80 chambers 13 is a series of electric lamps 18 connected with one or more approved batteries 19 within the chamber 14. The lamps 18 of each series are, as particularly brought 85 out in Fig. 5, disposed behind the border of the adjacent side wall of the cabinet so that light from said lamps will not shine directly through the apertures 17. The interior surfaces of the walls of the light chambers are 90 preferably painted or otherwise coated white so that a minimum number of lamps will be required to properly illuminate the 95 chambers. On the other hand, the exterior surfaces of the side walls 11 are preferably 100 painted or otherwise coated black. The purpose of thus coating the exterior surfaces of the side walls will presently appear.

Secured to the inner sides of the side walls 11 respectively adjacent each of the apertures 17 is, as particularly shown in Fig. 2, a socket or keeper 20 and supported by these sockets are shutters 21. The shutters may each be formed as a disk of suitable sheet metal provided at its periphery with a stem 105 or shank 22. These shanks are adapted to removably engage frictionally within the 110

sockets for supporting the shutters to seat flat against the inner faces of the side walls overlying the apertures for closing said apertures. Corresponding sides of the shutters 5 are preferably coated white while the opposite corresponding sides of the shutters are preferably coated black. The shutters are normally arranged with the black sides thereof presented outwardly. Consequently, 10 as will be clear, by reversing proper shutters so that their white sides will be presented outwardly, stencil letters may, as suggested in Fig. 1, be formed from each of the apertured fields in the side walls 11 and since the 15 outer faces of said side walls are coated black, the white letters defined by the reversed shutters will be clearly visible. The purpose in coating the outer sides of the side walls black, therefore becomes apparent. In 20 the manner indicated, not only letters may be defined from the apertured fields in the side walls but also any desired advertising device or word may be defined. I accordingly provide a cabinet wherein the signs 25 thereof may be readily changed or varied and, if desired, several sets of side walls may be employed in connection with the cabinet so that while one pair of side walls is in use, the work of forming a sign upon another 30 pair of side walls may progress coincidentally. For displaying a sign at night the proper shutters defining the sign are, instead of being reversed, simply removed. Then,

when the lamps 18 are energized, the sign will be illuminated.

35

Having thus described the invention, what is claimed as new is:

1. An advertising cabinet having a wall provided with a plurality of apertures there-through, sockets in the inner side of the wall 40 each immediately adjacent one of the apertures, and a plurality of shutters each having a shank removably and reversibly engaged in one of the sockets whereby the sockets will hold the shutters over the respectively adjacent openings, one face of each shutter being of the same color as the outer side of the wall and the opposite face of the shutter being of a contrasting color.

2. An advertising cabinet having a removable side wall provided with a many-aper-tured field, an imperforate border portion surrounding said field, the outer side of said wall and the inside of the cabinet being in contrasting colors, shutters supported on 55 the inner side of the wall each immediately adjacent one of the apertures in the wall to extend over said aperture, the shutters being selectively reversible and removable and the two sides of the shutters being in contrasting 60 colors, and an illuminating media arranged within the cabinet behind the imperforate border portion of the removable wall.

In testimony whereof I affix my signature.

CLARENCE E. CLOSSON. [L.S.]
